UNITED STATES PATENT OFFICE.

BERTHOLD HUBER AND WILLIS K. HODGMAN, OF TAUNTON, MASSACHUSETTS,
ASSIGNORS TO THE HUBER PRINTING PRESS COMPANY, OF SAME PLACE.

PRINTING-PRESS.

SPECIFICATION forming part of Letters Patent No. 544,809, dated August 20, 1895.

Application filed January 14, 1895. Serial No. 534,772. (No model.)

To all whom it may concern:

Be it known that we, BERTHOLD HUBER and WILLIS K. HODGMAN, of Taunton, county of Bristol, State of Massachusetts, have invented 5 an Improvement in Printing-Presses, of which the following description, in connection with the accompanying drawings, is a specification, like letters on the drawings representing like parts.

10 This invention relates to the class of "two-revolution printing-presses," so called, in which the impression-cylinder is continuously rotated and makes two revolutions while the reciprocating bed or form-carrier makes one 15 complete stroke, the impression-cylinder and form being slightly separated during the return of the latter. In such presses it is most essential to the production of good work that the registering shall be accurate—that is, dif- 20 ferent parts of the form must arrive opposite the same points on the cylinder at each impression—and we have attained such accuracy of register, especially at the points where the printing begins and ends, by positively moving the cylinder and bed or form-carrier in 25 unison at such points or adjacent thereto.

In accordance therewith our invention consists, in a two-revolution printing-press, of a rotatable impression-cylinder, circumferentially-separated toothed segments thereon laterally offset one from the other, a reciprocating form-carrier, longitudinally-separated racks thereon adjacent the head and tail of the form and respectively located in the paths 30 of the said segments, the racks and their co-operating segments being so located relatively to the center of the stroke that either segment will, in the back stroke of the form-carrier, move through a toothless space trans- 35 versely adjacent to the rack lying in the path of the other segment, substantially as will be described.

Other features of our invention will be hereinafter described, and particularly pointed 40 out in the claims.

Figure 1, in side elevation and partly broken out, represents a sufficient portion of a two-revolution printing-press to be understood with our invention applied thereto, with the 45 parts in the center of the printing-stroke. Fig. 2 is a detail view in elevation of the cyl-

inder and bed or form-carrier slightly separated and in the center of the backward or non-printing stroke; and Fig. 3 is a plan view, broken away, of the bed and form, showing 55 one arrangement of the register-racks thereon.

The frame A, of suitable shape to provide bearings for the operating parts, the impression-cylinder a, journaled in standards a', resting at their lower ends upon the eccentric 60 portions a² of a rock-shaft a³, suitably operated to keep the cylinder in contact with the form a⁴, supported by the bed or carrier a⁵, during the forward stroke of the bed and to raise the cylinder from contact with the form 65 during the return or backward stroke of the bed; the gear d, in mesh with and driving the gear d' on the cylinder-shaft d², and the mechanism for rotating the gear d and reciprocating the bed a⁵ are and may be substantially as shown in United States Patent No. 417,826, dated December 24, 1889, and form 70 no part of this invention.

The bed a⁵ is provided with a bearing a⁶, upon which runs the cylinder-bearing a⁷ during the printing-stroke of the press. A bar c is herein shown as secured to one side of the bed a⁵ by suitable set-screws c', extended through longitudinal slots c² in the bar into the bed, the bar having rack-teeth c³ formed 80 thereon at its upper edge adjacent the head of the form a⁴ and a second series of rack-teeth c⁴ adjacent the tail of the form, offset one from the other, to travel in separate parallel paths during the reciprocation of the 85 bed. The rack c⁴ is considerably longer than the rack c³, and the two are separated longitudinally by a blank space c⁵. A toothed segment d³ is secured to the impression-cylinder a in the same vertical plane as and to at 90 times mesh with the rack c³ on the bed, and a second toothed and longer segment d⁴ is secured to the said cylinder in the vertical plane of and to at times mesh with the rack c⁴, the segments being circumferentially separated 95 and so located as to mesh with their co-operating racks at the beginning and ending of the printing, whereby the cylinder and bed will be positively moved in unison at such times. By this means an accurate register is 100 attained, and it is impossible for one or the other to slip as the form begins or is finishing

the printing, the points where inaccuracy is otherwise most likely to occur.

In Fig. 1 the segment and rack d^3 and c^3 have just become disengaged, the bed moving 5 in the direction of the arrow, and the segment d^4 and rack c^4 are just about to engage to remain in mesh during the remainder of the printing, the cylinder and bed being thus locked together during the forward stroke for 10 the whole length of the form, except at the center of the stroke, where the bar c is cut away or plain at c^x . As the cylinder a continues to revolve after the impression is made it is slightly lifted from the bed as the latter 15 begins its backward stroke, and the segment d^3 sweeps around outside of the rack c^4 in a toothless space, so that there is no possibility of engagement therewith, and obviating the shortening of the teeth of either.

20 In Fig. 2 the bed is at the center of its backward stroke, and during the remainder of the stroke in the direction of the arrow the segment d^4 on the cylinder passes over the plain portion c^x of the bar c and inside of the path of 25 movement of the rack c^3 . By this arrangement of offsetting the racks and segments to move in different paths a very slight separation of the impression-cylinder and the form during the non-printing stroke of the bed is 30 sufficient. At the end of the second revolution of the cylinder the segment d^3 is in position to engage its rack c^3 for the next impression. The bars c are longitudinally adjustable on the bed by means of the slots c^2 35 and the set-screws c' , as may be necessary.

Our invention is not restricted to the form of press herein shown, as it may be applied to any two-revolution bed and cylinder printing-press, and instead of making the racks upon 40 a single bar each rack may be separately attached to the bed without departing from the spirit and scope of our invention. The relative lengths of the racks and co-operating segments may be altered so long as the engagement 45 one with the other locks the cylinder and bed at the beginning and ending of the printing.

It will be obvious that the end of the printing need not necessarily occur at the end of 50 the form, for the length of the matter to be printed will vary according to circumstances, and the length of the back segment and rack is sufficient to permit such variation in the 55 position of the end of the printing as will occur in practice.

Each rack is extended toward and as near

to the center of the stroke as possible without engaging its co-operating segment in the back stroke of the form-carrier, and this point we denominate the "clearance-point," and 60 have so designated it in the claims.

In the back stroke of the form-carrier the racks and segments are moving in opposite directions past the clearance-points, and were it not for the proper location of these points 65 the teeth would engage and be stripped.

The inner end of a rack moves away from its clearance-point as the co-operating end of its segment reaches it, or vice versa, as shown in Fig. 2, in the back stroke of the form-carrier. 70

We claim—

1. In a two-revolution printing press, a rotatable impression cylinder, circumferentially separated toothed segments thereon laterally offset one from the other, a reciprocating form-carrier, longitudinally separated racks thereon adjacent the head and tail of the form and respectively located in the paths of the said segments, the racks and their co-operating segments being so located relatively to the center of the stroke that either segment will, in the back stroke of the form-carrier, move through a toothless space transversely adjacent to the rack lying in the path 85 of the other segment, substantially as described. 75

2. In a two-revolution printing-press, a rotatable impression cylinder, a co-operating reciprocating form-carrier, separated racks on 90 said carrier located in different parallel vertical planes adjacent the head and tail of the former and extended therefrom toward the center of the stroke to the clearance point, and circumferentially separated segments on 95 the cylinder and respectively located in the paths of movement of said racks, to co-operate therewith singly in the forward stroke at the beginning and ending of the printing, the inner end of a rack moving away from the 100 clearance point as the co-operating end of its segment reaches it, or vice versa, in the back stroke of the form-carrier, substantially as described. 105

In testimony whereof we have signed our 105 names to this specification in the presence of two subscribing witnesses.

BERTHOLD HUBER.
WILLIS K. HODGMAN.
